BRACE

James H. Wallace, Wenatchee, Wash.

Application August 7, 1936, Serial No. 94,780

7 Claims. (Cl. 145—69)

This invention relates to braces or bitstocks for the reception of bits used in boring holes and the primary object of this invention is to provide a brace which will enable the user to bore holes in locations which are inaccessible with ordinary braces.

A more specific object of the invention is to provide a brace having an adjustable handle which may be selectively adjusted to occupy the usual position or to occupy a position at substantially right angles to the usual position when the brace is in use.

Other objects of the invention are to provide a brace of this nature which is strong, simple, and compact in construction, reliable and efficient in operation and not expensive to manufacture.

Other and more specific objects of the invention will be apparent from the following description taken in connection with the accompanying drawings.

In installing electric wires in buildings and in many other kinds of work necessitating boring holes in wooden structures it is often necessary to bore holes in places which are inaccessible to the usual brace and bit or even to ratchet braces or corner braces. It is an object of this invention to provide a brace in which the handle is adjustable into a position at substantially right angles to the axis of the bit receiving chuck and has a driving connection with the chuck when in this position thus adapting this brace for the boring of holes in locations inaccessible to ordinary braces.

In the drawing Figure 1 is a view in vertical section, with parts shown in elevation, of a bit brace constructed in accordance with my invention showing the brace handle in a position to be operated as an ordinary brace.

Fig. 2 is a similar view with parts broken away showing the brace handle positioned at substantially right angles to the axis of the bit holding chuck means for driving the chuck means through bevel gears.

Fig. 3 is a fragmentary sectional view with parts in elevation showing a pivotal joint and showing a locking sleeve in retracted position.

Fig. 4 is a fragmentary plan view of the ends of two members which are normally pivoted together but which are disconnected and spaced a short distance apart in said Fig. 4.

Fig. 5 is a detached view of a stub shaft which may be used to connect this boring means with a motor.

Fig. 6 is a sectional view, with parts in elevation,

of a modified form of chuck which may be used in this brace.

Like reference numerals designate like parts throughout the several views.

Referring to the drawing, 10 designates a tubular chuck housing. A bearing tube 11 extends outwardly from the upper end portion of the chuck housing 10. The bearing tube 11 is rigidly connected with the chuck housing 10 and is positioned at substantially right angles to the axis 10 of said chuck housing. A forked chuck frame is rotatably mounted in the chuck housing. This chuck frame comprises two side members 12, see Fig. 2, providing therebetween a space in which two chuck jaws 13 are operatively disposed. The upper end portions of the chuck jaws 13 are connected by pivots 14 with the side members 12. The lower ends of the chuck jaws are of conventional shape for the reception, in the usual manner, of the shank end of a bit or boring tool not shown. The upper end of the chuck frame is rigidly secured to a bevel gear 15. Ball bearings 16 are preferably provided between the base portion of the bevel gear 15 and the chuck housing 10. Upward thrust on the chuck housing is borne by a single centrally positioned ball 17 interposed between the bevel gear 15 and a cap 18 which is threaded into the upper end of the chuck housing. The top of the cap 18 is preferably rounded, as shown, to provide a convenient member upon which downward pressure may be exerted by the hand when the tool is in use with the brace handle in the position shown in Fig. 2. The lower ends of the chuck jaws 13 are moved toward each other to clamp a boring tool by means of a clamping ring 19 which is threaded onto the side members 12 of the chuck frame and has an inclined skirt portion 20 which engages with inclined portions 21 on the exterior of the chuck jaws 13. The upper end of the clamping ring 19 fits inside of the chuck housing 10 and said clamping ring 19 is provided with a flange portion 22 which may be grasped to turn said clamping ring.

A shaft 23 is journaled in the bearing tube 11 and a bevel gear 24 is positioned within the chuck housing 10 in mesh with the bevel gear 15 and secured on the end of the shaft 23. Ball bearings 25 are provided between the bevel gear 24 and the chuck housing 10. The outer end of the shaft 23 projects beyond the end of the bearing tube 11 and is provided with a split 26, see Fig. 4, for the reception of a flat tongue 27 on the end of a hand hold portion 28 of a crank member. A pivot 29 pivotally secures the hand hold portion 28 to the shaft 23 in such a manner that these

two parts may be moved into a position substantially at right angles to each other as shown in Figs. 1 and 3 or substantially in alignment with each other as shown in Fig. 2. One corner of the hand hold portion 28 is preferably rounded off as indicated at 30 to allow relative angular movement of parts 23 and 28. A sleeve 31 is slidably mounted on the hand hold portion 28 and urged toward the shaft 23 by a spring 32. A locking member 33 projects from the end of the sleeve 31 adjacent the shaft 23. When the hand hold portion 28 is in the position shown in Fig. 1, the locking member 33 extends past the end of the shaft 23 and holds the hand hold portion 28 at substantially right angles to the shaft 23. By sliding the sleeve 31 away from the shaft 23, as shown in Fig. 3, the locking member 33 may be moved clear of the shaft 23 and the hand hold portion 28 may be angularly moved on pivot 29 into substantial alignment with the shaft 23, as shown in Fig. 2, whereupon the spring 32 will move the sleeve 31 back toward the shaft 23 and position the locking member 33 alongside of the split end portion of the shaft 23. When the locking member 33 is in the position shown in Fig. 2, it will maintain the hand hold portion 28 in substantial alignment with the shaft 23 until the sleeve 31 is again retracted. A grip member 34 is rotatively mounted on the sleeve 31 between two collars 35 and 36 which are secured to the sleeve 31. A thrust collar 37 is secured to the hand hold portion 28 to support the upper end of the spring 32. A crank arm portion 38 is rigidly connected with the upper end of hand hold portion 28 and extends at substantially right angles therefrom and a knob receiving portion 39 is provided on the end of crank arm 38. A knob, preferably formed of a wooden member 40 supported between two metal members 41 and 42, is provided on the knob receiving portion 39. A screw 43 threaded through holes in the members 41 and 42 has its inner end positioned in a groove 44 in the knob receiving portion 39 thus preventing removal of the knob and at the same time permitting rotation of said knob.

The portions 31, 38 and 39 constitute a crank shaped handle member for imparting rotation to the chuck means. When the several parts are in the position shown in Fig. 1, the device may be used as an ordinary brace, the shaft 23 being held so that it can not rotate in the tube 11 and the bevel gears 15 and 24 preventing rotation of the chuck mechanism in the chuck housing 10. When holes are to be bored in locations which do not permit the brace to be used in the form shown in Fig. 1, then the crank shaped handle member is adjusted into the position shown in Fig. 2, and the shaft 23 rotated to drive the chuck means. When thus used the knob 40—41—42 serves as a handle and the tool is held steady and pressure for feeding is exerted by placing the hand on the upper end of the chuck housing.

Preferably the bevel gear 15 is larger than the bevel gear 24 providing power step up means for driving the chuck mechanism through said bevel gears.

In Fig. 5, I have shown means for connecting the shaft 23 of this boring tool with a power actuated driving means. In Fig. 5, the shaft 23 and brace handle parts are replaced by a straight stub shaft 55 having a slideable sleeve 56, hand hold 57, locking means 58, spring 59 and collar 60 similar to the corresponding parts previously described in connection with Figs. 1 to 4. A ball

bearing 61 is provided to receive the thrust of spring 59. The end of the stub shaft 55 extends beyond the collar 60 far enough so that it may be connected with an electric motor or other power actuated means, not shown.

In Fig. 6, I have shown an alternative form of chuck for use with this invention. This chuck comprises a chuck housing 45 carrying a rotatable chuck frame 46 within which two chuck jaws 47 are mounted by means of pivots 48. These jaws are forced together to clamp a bit by means of a forked clamping member having two wedge shaped prongs 49 connected by an upper portion 50. The prongs 49 are operatively disposed in suitable openings 51 in the chuck frame 46. A ball bearing 52 is interposed between the upper portion 50 of the clamping member and a screw cap 53. By screwing down the cap 53 the wedge shaped prongs 49 are forced downwardly between the outer walls of the openings 51 and the jaws 47 thus clamping the jaws securely onto any bit which may be inserted between said jaws. The ball 52 operates with relative freedom under the pressure needed to maintain the jaws 47 in clamped position.

The foregoing description and accompanying drawing clearly disclose a preferred embodiment of my invention but it will be understood that this disclosure is merely illustrative and that such changes in the invention may be made as are fairly within the scope and spirit of the following claims.

I claim:

1. In a boring tool of the class described, a chuck housing; chuck means rotatable within said chuck housing; a shaft journaled in said chuck housing and extending at substantially right angles therefrom; a bearing tube for said shaft rigid with said chuck housing and forming a lever arm by which said chuck housing may be rotated when the tool is operated as an ordinary brace; driving means providing a driving connection between said shaft and said chuck; and a crank shaped handle pivotally connected with the outer end of said shaft adjustable into two positions at substantially right angles relative to each other for selectively providing rotation of said shaft or rotation of said chuck housing.

2. In a boring tool of the class described, a chuck housing; chuck means rotatable within said chuck housing; a shaft journaled in said chuck housing and extending at substantially right angles therefrom; a bearing tube for said shaft rigid with said chuck housing and forming a lever arm by which said chuck housing may be rotated when the tool is operated as an ordinary brace; driving means providing a driving connection between said shaft and said chuck; a crank shaped handle pivotally connected with the outer end of said shaft; and releasable locking means connecting said handle with said shaft providing adjustment of said handle into two positions relative to said shaft, rotation of said handle when in one position driving said chuck through said shaft and said driving means and rotation of said handle when in the other position rotating said chuck, said chuck housing, said shaft, and said handle all about a common axis.

3. In a boring tool of the class described, a chuck housing; chuck means rotatable within said chuck housing; a shaft journaled in said chuck housing and extending at substantially right angles therefrom; a bearing tube for said shaft rigid with said chuck housing and form-

ing a lever arm by which said chuck housing may be rotated when the tool is operated as an ordinary brace; driving means providing a driving connection between said shaft and said chuck means; a crank shaped handle pivotally connected with the outer end of said shaft; and a sliding member on said crank shaped handle adapted to lock said handle in two positions relative to said shaft, selectively providing for the driving of said chuck by rotation of said shaft or for rotating said chuck by revolving said shaft along with said chuck housing about the axis of said chuck.

4. In a boring tool of the class described, a chuck housing; chuck means rotatable within said chuck housing; a shaft journaled in said chuck housing and extending at substantially right angles therefrom; a bearing tube for said shaft rigid with said chuck housing and forming a lever arm by which said chuck housing may be rotated when the tool is operated as an ordinary brace; driving means providing a driving connection between said chuck and said shaft; a one piece crank shaped handle embodying a crank arm provided at one end with a perpendicular hand hold portion and at the other end with a perpendicular knob receiving portion, said hand hold portion and said knob receiving portion extending in opposite directions from said crank arm; means pivotally connecting the end of said hand hold portion with the end of said shaft; and releasable locking means slidable on said hand hold portion into retracted or engaged position relative to said shaft adapted to lock said hand hold portion in a position substantially parallel to said shaft or in a position at substantially right angles to said shaft.

5. In a boring tool of the class described, a chuck housing; chuck means rotatable within said chuck housing; a shaft journaled in said chuck housing and extending at substantially right angles therefrom; a bearing tube for said shaft rigid with said chuck housing and forming a lever arm by which said chuck housing may be rotated when the tool is operated as an ordinary brace; driving means providing a driving connection between said chuck and said shaft; a crank shaped handle embodying a crank arm provided at one end with a rigidly connected perpendicular hand hold portion and at the other end with a rigidly connected perpendicular knob receiving portion extending in an opposite direction from said hand hold portion; a hand hold on said hand hold portion; means pivotally connecting the end of said hand hold portion with the end of said shaft; and releasable locking means slidable on said hand hold portion into retracted or engaged position relative to the end of said shaft adapted to lock

said hand hold portion in a position substantially parallel to said shaft or in a position at substantially right angles to said shaft.

6. In a boring tool of the class described, a chuck housing; chuck means rotatable within said chuck housing; a fixed bearing tube extending outwardly from the upper portion of said housing and providing a lever arm by which the chuck housing may be rotated when the tool is operated as an ordinary brace; a shaft journaled in said bearing tube; bevel gear means providing a driving connection between said chuck and said shaft and locking said chuck against rotation within said chuck housing when said shaft is non-rotatably held; a crank shaped handle pivotally connected with the outer end of said shaft; and releasable locking means slidable on said handhold portion into retracted or engaged position relative to the end of said shaft adapted to lock said crank handle to said shaft in different positions respectively with the connected portions of said crank handle and said shaft substantially in alignment with each other or at substantially right angles to each other.

7. In a boring tool of the class described, a chuck housing; chuck means rotatable within said chuck housing adapted to receive and hold a bit; chuck adjusting means connected with said chuck for clamping said chuck onto a bit; ball bearing means supporting said chuck within said chuck housing; a tubular lever arm extending at substantially right angles from the upper portion of said housing, a shaft rotatable in said tubular lever arm; bevel gears providing a driving connection between said chuck and said shaft; a crank shaped handle embodying a crank arm provided at one end with a perpendicular hand hold portion and at the other end with a rigidly connected perpendicular knob receiving portion extending in an opposite direction from said hand hold portion; a combined thrust knob and handle on said knob receiving portion; a hand hold slidable on said hand hold portion; means pivotally connecting the lower end of said hand hold portion with the outer end of said shaft; and locking means on said slidable hand hold locking said hand hold portion in a position at substantially right angles relative to said shaft or in a position substantially parallel to said shaft, whereby said chuck may be rotated within said chuck housing through said bevel gears by rotating said crank handle when said hand hold portion is parallel to said shaft and whereby said chuck housing and said chuck may be rotated bodily with said brace handle when said hand hold portion is positioned at right angles to said shaft.

JAMES H. WALLACE.
